CONTACT SELECTING FINGER FOR
CROSSBAR SWITCHES

Erik Axel Wiberg and Ernst Henrik Paulander,
Stockholm, Sweden, assignors to Telefonaktie-
bolaget L M Ericsson, Stockholm, Sweden, a
company of Sweden

Application January 30, 1945, Serial No. 575,296
In Sweden March 13, 1944

2 Claims. (Cl. 179—27.54)

1

The present invention relates to a selecting finger for cross-bar switches. In a switch of this kind for indication of the spring group to be actuated by means of a horizontal operating bar, a number of vertical selecting bars with, as a rule, rigidly mounted indication wires or contact selecting fingers are used. An object of the present invention is to provide a suitable construction for such a selecting finger which is not connected with the pertaining selecting bar. According to 10 the invention and with the foregoing and other objects in view the indicating member consists of a rigid finger which lies entirely outside the pertaining selecting bar and which is arranged to be acted upon by said bar only when the corresponding operating bar has its inactive normal position.

The invention will hereinafter be more fully described with reference to accompanying drawing which shows an example of a contact selecting finger according to the invention and its use in a cross-bar switch. Figs. 1 and 2 are side views of the cross-bar switch and Fig. 3 is a plan view. The drawing illustrates only that part of the cross-bar switch which is required for a clear understanding of the invention. The switch may be of any known construction.

Each vertical selecting bar 11 contained in the cross-bar switch is mounted to turn about pivot pins 11a and is provided with two armatures 13 and 14 which are arranged to be acted upon by the related magnets 15 and 16 respectively. This makes it possible for a selecting bar with arms 17 mounted thereon to be turned in different directions. According to the invention a special selecting finger 21 is provided for each arm 17, said selecting finger being rigid. In that way each selecting bar has arms with pertaining selecting fingers up to a number corresponding to the number of operating bars contained in the switch. Each selecting finger 21 is pivotally supported at 23 in a bridle 22. The bridle 22 is rotatably mounted around the points 24 and may be acted upon by the operating bar 12 of the corresponding switch so as to be rocked upwardly and downwardly when the magnet 18 acts upon the bar. The bar 12 is arranged to support a number of selecting fingers which corresponds to the number of selecting bars in the cross-bar switch. The selecting fingers are provided, adjacent the arm 17, with a claw which normally encircles the extremity of arm 17, Figs. 2 and 3. When the operating bar 12 is attracted and the bridle 22 is raised, the selecting fingers associated with the operating bar will be disengaged from the corresponding arm 17, Fig. 1. All the mechanism thus far described is mounted in known manner in the rack 20, 33 of the switch, as is also the case with the contact spring groups 31 of the switch.

2

When, for example, the magnet 15 pertaining to selecting bar 11 is magnetised it moves the bar 11 from the normal position shown by continuous lines in Fig. 3 into the broken line position. The arm 17 thereby transmits that movement to selecting finger 21 which is turned about the pivot 23 into the broken line position. The foremost part of the selecting finger will be moved to a position between operating bar 12 and the right-hand spring group 31, Fig. 3, which is thus put under the control of the selecting finger. When thereafter the bar 12 is actuated, it raises its bridle 22 and the selecting finger 21 and the latter, by means of a strip 32 actuates all the movable contact springs in said right-hand contact spring group 31. As previously mentioned, the selecting finger 21 is released from the selecting bar and the arm 17 when the bridle is raised, and it now takes the position in relation to the arm 17 as indicated in Fig. 1. Thus, the selecting bar 11, when the operating bar is actuated, is completely released from the selecting finger 21. When the magnet of the operating bar is demagnetised the bridle 22 returns to normal position according to Fig. 2 and the selecting finger 21 may again be actuated by the arm 17.

We claim:

1. In a cross-bar switch, a movable vertical selecting bar, a movable horizontal operating bar, two groups of contacts adjacent said selecting bar, a rigid selecting finger movable into operative positions with respect to either of said groups of contacts, a horizontal bridle supporting the selecting finger and operated by the horizontal operating bar from a normal unoperated position to an active position, means on said selecting bar effective when said bridle is in its unoperated position to move said selecting finger into either operative position whereby upon actuation of the operating bar the operatively positioned finger is caused to actuate the related group of contacts.
2. A cross-bar switch as claimed in claim 1 wherein said finger is disengaged from said selecting bar when the latter is in its active position.
